UNITED STATES PATENT OFFICE.

PERCY H. WILSON AND CHARLES H. SAPPER, OF NORFOLK, VIRGINIA.

LOUVRE-BLIND SLAT AND CLIP.

1,327,364.

Specification of Letters Patent.

Patented Jan. 6, 1920.

Application filed May 1, 1918. Serial No. 231,954.

To all whom it may concern:

Be it known that we, PERCY H. WILSON and CHARLES H. SAPPER, citizens of the United States, and residing at Norfolk, 5 county of Norfolk, State of Virginia, have invented certain new and useful Improvements in Louvre-Blind Slats and Clips, of which the following is a specification.

This invention relates to louvre blinds 10 and more particularly to devices for carrying the slats of the blind.

The objects of the invention are to provide a device for carrying the slats of a louvre blind and supporting them on the 15 blind collapsing means, without in any way cutting or perforating the slats, and which requires no fastenings, such as screws or nails, to secure the device to the slat; to provide an imperforate slat in combination 20 with a clip which is detachably secured to the slat; to provide a clip which is secured to a slat by clamping the opposite edges thereof; to provide a clip which does not require that the slats be of an exact 25 width; to provide a clip which may be manufactured at a low cost; and generally to provide a simple, efficient, and light device of the type mentioned. Other objects and features of novelty will be apparent 30 from the description taken in connection with the drawings in which:

Figure 1 is an inside elevation of a frame having a louvre blind of the type with which we prefer to use the devices constituting the subject matter of this application; 35

Fig. 2 is a transverse sectional view of the top portion of the blind and frame and illustrating one manner of supporting the 40 slat carrying clips;

Fig. 3 is a perspective view of one form of clip;

Fig. 4 is a perspective view of a slat having two clips clamped thereon;

Fig. 5 is a perspective view of one end of 45 a clip showing a modified form of eye at the end of the clip;

Fig. 6 is a perspective view of another form of clip.

In order to fully disclose the manner of 50 using and assembling the devices of the present invention in a louvre blind, it has been illustrated in connection with a blind of the type described and claimed in our application Serial No. 231,953, filed May 1, 55 1918,

Referring to the drawings it will be seen the blind is shown in the usual frame 10 of a window, although it is to be understood that the use of the blind is not limited to windows, but may be employed in other locations and for other purposes. As shown, a top support 11 is provided and this support has the spaced depending angle brackets 12 in which the shaft 13 is 60 rotatively mounted. The ends of the shaft project outside said brackets 12 and carry the sprocket wheels 13' which are arranged within the partial housings 14 and have chains 15 and 16 passing over the same, 65 these chains being provided for the purpose of collapsing the blind. The brackets 12 in addition to the shaft 13 also pivotally support the top slat 17. This slat is adapted to be rocked on its pivots by any suitable 70 means. As shown, for this purpose a toothed segment 18 is secured to the slat and meshes with a worm 19 rotatively supported in the brackets 20 fastened to the support 11. The axis of the worm extends 75 transversely of the slats and the worm is rotatively connected with a sprocket 21 arranged so that the chain 22 passing over the same may hang without interfering with the slats. Thus when the chain 22 80 is pulled in one direction or the other, the top slat 17 will be rocked on its pivots. As will be described hereinafter, the tilting or 85 rocking of this top slat is communicated to the other slats of the blind for opening and closing the spaces between the same.

For the purpose of holding the slats parallel and in spaced relation when the blind is extended and also permitting the progressive and successive collapsing of the slats, a 90 novel tape of jointed metal links may be provided, this tape being described and claimed in our application renewal Serial Number 238,826, filed November 19, 1919. Preferably, there are two pairs of metal tapes, 95 one of each pair being at the front and the other at the rear of the blind. As shown in Figs. 1 and 2, these tapes comprise a series of rigid links 23 pivotally connected together at their ends. For this 100 purpose the end of one link is slightly offset as at 24 and the adjacent end of the adjoining link is off-set in the opposite direction as at 25, and these two off-set portions are pivotally connected as by means 105 of a pin 26. As shown in Fig. 2, this construction permits the links to be arranged

so that as viewed on edge they are in substantially midway of their length with apertures for pivot pins 30, these pins pivotally supporting the slat carrying devices which 5 constitute the subject matter of this application.

Although a specific arrangement of blind and a specific form of tape for spacing the slats of the blind and collapsing them have 10 been described, it is to be distinctly understood that the slat carrying devices are adapted for use in connection with other forms of tapes or blind collapsing means and other arrangements of the blind. As 15 clearly shown in Fig. 2, the slat carrying devices are interposed between the front and rear tapes and secured to said tapes so that they are always held in substantially parallel relation.

20 Referring now to Figs. 3, 4 and 5, the slot bearing device or clip may be formed from a wire stock bent up to form the hook or slat edge engaging parts 31. Intermediate the hook portions the wire may be formed with 25 an S-shaped spring portion 32 which acts to draw the hooks 31 toward each other to thereby clamp the slat. Preferably, these hook portions are formed by bending the wire back on itself as shown and the free 30 ends are bent to form eyes 33, one manner of bending the free ends being shown in Fig. 3 and another in Fig. 5, the eye being shown at 33' in the latter figure. As the hooks are formed of two thicknesses of wire, 35 it will be seen that they have considerable rigidity so that they will not be bent out of shape in attaching and removing the clip. The eyes 33 are provided for the purpose of pivotally connecting the clips to the tapes 40 of the blind and it will be seen that the slats S may be assembled in the blind merely by separating the hooks 31 to permit the edges of the blind to pass the same and then allow the spring portion 32 to pull the hooks together 45 so that they clamp the slat. Thus no perforations are formed in the slats and no screws or nails are required to secure the clips to the slats and consequently the cost of manufacture of the slats is limited merely 50 to sawing them to the proper lengths. Furthermore, this construction permits the owner of the blind to replace a broken slat, the operation of removing and inserting a slat being so simple that any one can 55 form it. Moreover the construction of the clips is such that slight variations in the widths of the slats are permissible.

60 A modified form of clip is illustrated in Fig. 6. This clip may be pressed up from a strip of thin metal and comprises the hook portions 40 and the end tabs 41. Prior to forming the hooks 40 the strip is cut to form the tongues 42 adapted to be bent into the

position shown at the left of the clip of Fig. 6 so that the end of the tongue engages 65 on the top surface of the slat, the apertures left by bending up the tongues forming eyes 43 for pivotally connecting the clip to the tapes of the blind. In applying a slot to the clip one edge of the blind is slipped 70 under the left-hand tongue of Fig. 6 and then the opposite edge is pushed down and passes the vertical tongue 42 until the central portion 44 of the clip lies flat against the lower surface of the slat. Then the vertical tongue 42 is bent down against the 75 upper surface of the slat. In this manner the clip is securely fastened to the slat and yet the slat may be removed by merely bending one of the tongues 42 up into vertical 80 position.

Although a specific structure has been described, it is understood that changes may be made without departing from the spirit of the invention as set forth in the appended 85 claims.

Having thus described the invention what is claimed as new and desired to be secured by Letters Patent is:

1. As an article of manufacture, a clip 90 for the slats of louvre blinds having a hook at one end adapted to engage the edge of a slat, a part at the other end formed to engage the opposite edge of the slat, and an intermediate spring portion for drawing 95 said hook and part together to clamp the slat.

2. As an article of manufacture, a clip for the slats of louvre blinds having a hook adapted to engage an edge of a slat, another 100 hook adapted to engage the opposite edge of the slat, and means for pulling the hooks toward each other to clamp the slat between said hooks.

3. As an article of manufacture, a clip for 105 the slats of louvre blinds having a hook adapted to engage an edge of a slat, another hook adapted to engage the opposite edge of the slat, and spring means for pulling the hooks toward each other to clamp the slat 110 between said hooks.

4. As an article of manufacture, a clip for the slats of louvre blinds including hooks adapted to engage the opposite edges of the slat, each end of the clip being formed with 115 an eye.

5. As an article of manufacture, a clip for the slats of louvre blinds including end parts adapted to engage the opposite edges of a slat and an S-shaped spring portion 120 intermediate said parts adapted to lie flat against the slat.

In testimony whereof we affix our signatures.

PERCY H. WILSON.
CHARLES H. SAPPER,
